UNITED STATES PATENT OFFICE.

WILLIAM G. HOUSKEEPER, OF PHILADELPHIA, PENNSYLVANIA, ASSIGNOR TO
WESTINGHOUSE LAMP COMPANY, A CORPORATION OF PENNSYLVANIA.

TERMINAL DEVICE.

1,099,090.

Specification of Letters Patent.

Patented June 2, 1914.

Application filed March 31, 1909. Serial No. 486,926.

To all whom it may concern:

Be it known that I, WILLIAM G. Hous-
keeper, a citizen of the United States, and a
resident of Philadelphia, in the county of
5 Philadelphia and State of Pennsylvania,
have invented a new and useful Improve-
ment in Terminal Devices, of which the fol-
lowing is a specification.

My invention relates to electrical terminal
10 devices, and it has for its object to provide a
device that is adapted to make electrical
contact with continuously or progressively
moving conductors, such, for instance, as the
filamentous material that is used in the
15 preparation of filaments for incandescent
lamps, though it is not limited to such uses.

In another application, Serial No. 486,925,
filed of even date herewith, by another and
20 myself, is set forth a process of, and appa-
ratus for, continuously preparing filaments
for incandescent lamps, and, particularly,
filaments composed of or containing tung-
sten. One of the steps in the said process
25 consists in supplying electric current to
progressively moving filamentous material
at intervals of its length. In practising the
said process, it is extremely important and
quite essential that the terminal device,
30 whereby current is supplied to moving fila-
mentous material at intervals of its length,
should not materially retard the movement
thereof and require placing the material
under undue strain in order to effect its
35 movement. The movement of the conductor
should, therefore, be accompanied by very
little friction, and the terminal devices must,
accordingly, be constructed to avoid it. It
is also essential that the terminal devices
40 shall always make such good contact with
the moving material that no arcs or burning
will occur between them, in order that the
material may not be ruptured. The present
device fully meets these requirements and
45 permits successful practising of the above
stated process.

Figure 1 of the accompanying drawing is
a face view of a terminal device constructed
in accordance with the present invention,
and Fig. 2 is a sectional view through the
50 device.

The main member 1 of the terminal, which
may be supported in any suitable manner,
such as that shown, is provided with an
aperture at 2 through which the filamentous
55 material or conductor 3 is adapted to pass.

The member 1 is preferably composed of
copper and its edges are amalgamated in
order to increase the degree of adhesion be-
tween the member and a body of mercury 4
that substantially fills and extends across the 60
aperture. The body of mercury within the
aperture is provided with concave faces, by
carefully wiping, or otherwise removing, the
excess of mercury from both faces of the
member 1, the surface tension of the mer- 65
cury then serving to force the filament to
the center of the aperture in the member 1
and to maintain it out of engagement with
the said member. The surface tension of
the mercury is also sufficient to maintain it 70
in the aperture even during progressive
movement of the conductor, and but a very
slight amount of strain need be placed upon
the conductor in order to effect its longi-
tudinal movement, because the friction of 75
the mercury therewith is almost negligible.
Moreover, the mercury makes excellent con-
tact with the conductor, and there is no arc-
ing between the conductor and the terminal,
with the result that the conductor is never 80
ruptured at or near the terminal device.

While the member 1 is preferably com-
posed of copper, which may be readily
amalgamated, it may, if desired, be merely
coated or plated with copper, or it may be 85
composed of other materials that may be
amalgamated. Mercury may be replaced,
also, by another suitable metal in fluid con-
dition, such as molten tin, in which case the
edges of the aperture in the member 1 would 90
preferably be tinned, or it may be replaced
by any other conducting fluid.

I claim as my invention:

1. A device of the character described
comprising an apertured member, and a 95
body of mercury extending across the aper-
ture and attached to its edges.

2. A device of the character described
comprising an apertured member, and a
body of mercury having concave faces ex- 100
tending across the aperture.

3. A device of the character described
comprising an apertured member the por-
tion of which surrounding the aperture is
amalgamated, and a body of mercury ex- 105
tending across the aperture.

4. A device of the character described
comprising an apertured member the por-
tion of which surrounding the aperture is
amalgamated, and a body of mercury hav- 110

- ing concave faces extending across the aperture.
5. A device of the character described comprising an apertured member, and a body of metal in fluid condition extending across the aperture and attached to its edges.
6. A device of the character described comprising an apertured member, and a body of metal in fluid condition extending 10 across the aperture and having concave faces.
7. A device of the character described comprising an apertured member and a body of metal in fluid condition extending 15 across the aperture, the portion of the member surrounding the aperture being coated with a material for which the said body of fluid metal has a considerable degree of attraction.
- 20 8. A device of the character described comprising a body of mercury and an amalgamated supporting member having an aperture in which the said body is suspended.
9. A device of the character described 25 comprising a body of liquid metal and a supporting member therefor for which the liquid metal has a positive degree of capillary attraction and having an aperture in which the said body is suspended.
- 30 10. A device of the character described comprising a member having amalgamated separated parts and a body of mercury suspended between the said parts.
11. A device of the character described comprising an amalgamated member having 35 an aperture and a body of mercury suspended by its own surface tension from the walls of said aperture.
12. A device for engaging a longitudinally movable filament comprising a body 40 of mercury completely surrounding the filament, and an amalgamated supporting member from which the said body is suspended.
13. A device for engaging a longitudinally movable filament comprising a liquid 45 conducting body completely surrounding the filament, and a supporting member from which the said body is suspended.
14. A device for engaging a longitudinally movable filament comprising a body of 50 mercury that completely surrounds the filament and a support from which the body of mercury is suspended by its own surface tension.
15. A device for engaging a longitudinally movable filament comprising a liquid 55 conductor completely surrounding the filament and means from which said conductor is suspended by its own surface tension.

In testimony whereof, I have hereunto subscribed my name this twentieth day of March, 1909.

WILLIAM G. HOUSKEEPER.
